BOTTLE

John B. Onthank, Atlanta, Ga., assignor, by mesne assignments, to Canada Dry Corporation, New York, N.Y., a corporation of Delaware

Filed June 18, 1968, Ser. No. 12,400

Term of patent 14 years

Int. Cl. D9—01

U.S. Cl. D9—114

FIG. 1

FIG. 2

FIG. 1 is an elevation of a bottle showing my new design; and

FIG. 2 is a bottom plan view thereof.

The ornamentation seen on the lower portion of FIG. 1 continues around the remainder of the bottle in the staggered relationship shown.

I claim:

The ornamental design for a bottle, as shown and described.
